US00D940149S

(12) **United States Design Patent** (10) Patent No.: **US D940,149 S**
Pillalamarri et al. (45) Date of Patent: **** Jan. 4, 2022**

(54) **DISPLAY SCREEN WITH A GRAPHICAL USER INTERFACE**

3,614,554 A 10/1971 Shield
 3,983,077 A 9/1976 Fuller et al.
 4,313,439 A 2/1982 Babb et al.

 4,898,578 A 2/1990 Rubalcaba, Jr.
 4,967,201 A 10/1990 Rich, III

(71) Applicant: **INSULET CORPORATION**, Acton, MA (US)

(72) Inventors: **Sandhya Pillalamarri**, Methuen, MA (US); **Jorge Borges**, Billerica, MA (US); **Viki Schrager**, Acton, MA (US)

(73) Assignee: **INSULET CORPORATION**, Acton, MA (US)

(**) Term: **15 Years**

(21) Appl. No.: **29/686,757**

(22) Filed: **Apr. 8, 2019**

Related U.S. Application Data

(62) Division of application No. 29/606,901, filed on Jun. 8, 2017, now Pat. No. Des. 874,471.

(57) **CLAIM**

The ornamental design for a display screen with a graphical user interface, as shown and described.

DESCRIPTION

The FIGURE is a front view of a display screen with a graphical user interface showing our new design.

The broken lines showing a display screen and elements of the graphical user interface illustrate portions of the article, and form no part of the claimed design.

1 Claim, 1 Drawing Sheet
